UNITED STATES PATENT OFFICE

SWAN E. NORD, OF SEATTLE, WASHINGTON

SELF-DRAINING OIL CAN

Application filed October 23, 1928. Serial No. 314,524.

This invention has reference particularly to improvements in the standard can commonly used by wholesalers of lubricating oil in making deliveries to retailers. The 5 practice is to transport the oil in cans of convenient size for handling, and in making a delivery the purchaser is charged for the full contents of the can, which, in such a can, amount to five gallons. In pouring the oil 10 in the usual way, I have ascertained by experiments that a residue of approximately one pint of oil will remain in the can, owing to the viscous properties of the substance poured. 15 The objects of my invention, generally stated, are, to provide an oil can standard in size and general construction, but equipped with an extension to its body portion, disposed adjacent the neck of the can, which 20 permits the can to be inverted and said residue to drain into the hollow and detachable top common to such cans, without seepage of oil from the can, and thereby practically eliminating the loss of said residue; to provide means whereby any oil remaining in the 25 top, after the residue is recovered therefrom, may drain back into the body of the can, thus keeping the top free from drained oil; and, to provide simple but effective instru- 30 mentalities for achieving the results attained.

In the accompanying drawing—

Figure 1 is a front elevation of an oil can, including the device, the can being partly 35 sectionized and broken away to illustrate the construction more clearly;

Fig. 2, a sectional view of the detachable top, neck and portion of can body, inverted, showing the device and oil as drained into 40 the top;

Fig. 3, a cross section drawn along the line 3—3, of Fig. 1;

Fig. 4, a vertical section of the upper portion of can body and the neck, showing a 45 modified form of the device; and,

Fig. 5, a top view of a split collar utilized in the modified construction.

Referring more particularly to the drawing, the base 1, neck 2, cylindrical body portion 50 of the top 3, closure for the top 4, in-

cluding a laterally extending rim, and the handle 5, swingingly mounted to the can, are of ordinary construction. The body portion of the can 6, cylindrical in form, is surmounted by a portion 7, in the form of a truncated cone, said portions comprising the container, and are shown in the drawing as of smooth construction, and, with the exceptions to be detailed, are of usual form. In 55 common cans of this class, the container is usually corrugated in different ways, to add strength to the structure, and if desired, this device may, with propriety, be applied to a can having a container of such construction.

As it may be noted in Fig. 1, in the preferred form of the device, the portion 7 is prolonged so that its free edge extends within the neck and provides, when the can is upright, a circumferential channel 8 within the neck, obviously disposed between said portion and the adjacent surface of the neck. Said prolonged portion is apertured, as at 9, to afford discharge ports through which oil drained from the top may be deposited in the container. When the can is reversed, as 70 shown in Fig. 2, the portion 7, disposed as it is slightly within the neck, will not only permit the residue of oil remaining in the can after pouring to drain into the top as shown, but will in fact, as it is provided with 75 a relatively sharp edge, facilitate and hasten said drainage. The discharge ports are located inwardly of the joint 10, formed by the telescopic connection of the body of the top with the neck; consequently the portion 80 7 will provide an oil-tight closure for said joint, and prevent seepage of oil from the can during the draining operation. When the top is placed in closed position within 85 the neck, the free edge of its body portion is out of contact with the portion 7, the outer edge of the neck providing an abutment for the top, as is usual in such cans.

In operating the device, after the oil has been poured from the can, the can, including the top, is inverted, when the residue of oil in the container will drain into the top. In removing the top from the inverted can, for recovering the drained oil therein, the operator may place either foot on the rim of the 90 100

top, to hold it securely in place, when the container, obviously, may be lifted therefrom. When the can is returned to an upright position and the top replaced, any residue of oil remaining in the top, after the drained oil is poured out of it, may then drain into the container.

The modified form of the device is particularly designed to make this invention conveniently applicable to oil cans of the ordinary type and which have been already constructed. In Fig. 4, 20 denotes a portion in the form of a truncated cone, which constitutes a part of the container, and is of common construction. To convert a can of this type into a self-draining one, and in accordance with this invention, I provide a flared collar 21, which is split as at 22, and carries a plurality of openings 23 which act as drainage ports. The split permits the collar to be contracted so that it may be inserted through the neck of the can and placed in the position shown in Fig. 4 and then soldered, or secured in any suitable manner, to the portion 20. When thus secured in place, it and the ports occupy identically the same positions in relation to the neck and top as heretofore described relative to the prolonged and apertured portion 7, and function in the same way.

Forms which the invention may assume have been exemplified in the description and drawing by way of examples, but it will be obvious to those skilled in the art that changes in and modifications of the construction described may be made without departing from the spirit of my invention or sacrificing its advantages, hence I ask that I be not confined to the specific structures set forth.

I claim:

1. A self-draining oil can, comprising a body portion, a neck, a top slidably engaged within the neck, an apertured extension to the body portion projected into the neck, providing, when the can is inverted, a member for diverting drainings of oil from the body portion away from the joint formed between the top and neck, in their sliding engagement, and directing the same into said top, and affording, when the can is upright, a circumferential channel located between the extension and the neck for draining oil from the top into the body portion.

2. In a self-draining oil can having a container surmounted by a flared portion, a neck for the portion and a top telescopically engageable within the neck, an integral prolongation of the portion defining, when the can is reversed, a hollow, inverted and truncated cone adapted to drain oil from the container into the top and to prevent oil seeping between the top and neck during the drainage operation, and, when the can is upright, an apertured channel, extending circumfer-

entially of the neck, for receiving and draining oil from the top into the container.

3. In a self-draining oil can having a container, a neck and a top telescopically engaged within the neck, an integral and apertured prolongation of the container, defining, when the can is reversed, a hollow, inverted and truncated cone opening into the neck, adapted to divert drainings of oil from the container away from the joint produced by the engagement of the top with the neck, and to direct said drainings into the top.

4. In a self-draining oil can having a body portion, a neck surmounting the body portion and a top slidably engaged within the neck, a prolongation of the body portion, defining, when the can is reversed, a hollow, inverted and truncated cone communicating with the neck, adapted to divert drainings of oil from the body portion away from the joint produced by the engagement of the top with the neck, and to direct said drainings into the top.
